2 SHEETS—SHEET 2.

UNITED STATES PATENT OFFICE.

ROSS M. G. PHILLIPS, OF WEST HAVEN, CONNECTICUT, ASSIGNOR TO THE SENTINEL MFG. CO., OF NEW HAVEN, CONNECTICUT, A CORPORATION.

BLOW-TORCH.

1,152,214.

Specification of Letters Patent. Patented Aug. 31, 1915.

Application filed October 3, 1914. Serial No. 864,781.

To all whom it may concern:

Be it known that I, Ross M. G. Phillips, a citizen of the United States, residing at West Haven, in the county of New Haven 5 and State of Connecticut, have invented a new and useful Improvement in Blow-Torches; and I do hereby declare the following, when taken in connection with the accompanying drawings and the characters of 10 reference marked thereon, to be a full, clear, and exact description of the same, and which said drawings constitute part of this application.

Figure 1 is a broken view in side elevation of one form which my improved blow-torch may assume. Fig. 2 is a broken plan view thereof. Fig. 3 is a broken view there- 15 of partly in elevation and partly in vertical longitudinal section. Fig. 4 is a broken view 20 partly in vertical section, and partly in side elevation of one of the modified forms which my improved blow-torch may as- 25 sume. Fig. 5 is a broken view partly in elevation and partly in section of another modified form which my invention may assume. Fig. 6 is a broken view in side elevation 30 of still another modified form of my improved blow-torch.

My invention relates to an improved blow- 35 torch of the kind used for brazing, welding, paint-removing and other kindred uses, the object being to provide a simple and convenient device constructed with particular reference to the convenient control of the gas- 40 content supplied to the mixture by the hand in which the torch is held at the time of using it, concurrently with the use of the torch, and without recourse to the use of the other hand which is thus left free.

With these ends in view, my invention 45 consists in a blow-torch having certain details of construction and combinations of parts as will be hereinafter described and pointed out in the claims.

As herein shown, I employ parallel gas and air-pipes 2 and 3 having their outer ends 50 respectively entered into two parallel sleeves 4 and 5 formed integral with a cast torch or delivery head 6 carrying an inwardly turned, mixing-tube 7 beyond the end of which the flame burns as usual in this class

of devices. The inner or handle ends of the said pipes 2 and 3 are as shown secured together and supported by a transverse strut 8. The gas-pipe 2 is furnished with a suitable gas-cock or valve 9 having a handle 10, while the air-pipe 3 is furnished with a suitable air-cock or valve 11 having a handle 12. The gas-pipe 2 is located on the outside of the torch with respect to the air-pipe 3 55 which is on the inside of the torch, but this arrangement may be reversed as will appear later on.

In carrying out my invention as shown in Figs. 1, 2 and 3, I provide a sliding valve- 60 manipulating device 13 made from a single piece of wire and mounted upon the outside of the gas-pipe 2 in position to be readily manipulated by the thumb of the hand in which the user is holding the torch. As 65 shown, the said sliding valve-manipulating device 13 is shaped at its inner end to form an operating-loop 14 which extends rear- 70 wardly over the gas-cock 9 directly in front of which the wire forming the device 13 is 75 bent to form two coils 15 and 16 which embrace the gas-pipe 2 and serve to guide the said device, the forward portion of which passes through a sheet-metal clip 17 applied to the gas-pipe 2 and held in place by 80 a screw 18. In front of the clip 17, the sleeve 4 of the head 6 is furnished with two lugs 19 between which the forward end of the device 13 passes and by means of which it is guided. At its extreme forward end 85 the wire forming the device 13 is bent to form a hook 20 by means of which the torch is suspended so as to hang in a vertical position when not in use. The inner arm 21 of the hook 20 co-acts directly with the head 90 22 of the stem 23 of a supplemental gas- valve 24 co-acting with a valve-seat 25 in the head 6 as shown in Fig. 3. The said valve-stem 23 is mounted in a gland 26 threaded into the head 6 and containing a 95 helical spring 27 surrounding the stem 23 and exerting a constant effort to hold the valve in its open position. When the wire valve-manipulating device 13 is pushed outward by the user of the torch, who presses 100 the loop 14 forward with his thumb, the arm 21 of the suspension-loop 20 cams against

the head 22 of the valve-stem 23 so as to overcome the tension of the spring 27 and entirely or partially shut off the gas at this time being supplied freely through the gas-
5 pipe 2 on account of the open position of the gas-cock 9. The said head 6 is formed with a passage 28 from which the gas passes into the inner end of the mixing-tube 7 which contains an air-nozzle 29 leading from the
10 forward end of the air-pipe 3.

By using the thumb to manipulate the sliding valve-manipulating device 13, the gas-content supplied to the flame of the torch may be easily controlled concurrently
15 with the use of the torch and without bringing the other hand of the user of the torch into requisition. The forward movement of the device 13 is stopped by the engagement of a shoulder 30 or bend in the wire with
20 the head 22 of the valve-stem 23, and its rearward movement by the engagement of the coil 16 of the wire with the forward end of the gas-cock 9. As shown, the torch is provided with a small pilot-light tube 32 leading forward from the rear end of the gas-
25 cock, and provided for relighting the torch as the exigencies of the work being done may require.

In using my improved torch, the cocks or
30 valves 9 and 10 are initially set to secure the mixture of air and gas required for producing the flame suited to the work at hand. The torch having been lighted, is now held in one hand and used in the ordinary manner.
35 If during the use of the torch it is desired to vary the gas-content of the flame, or to shut the gas off entirely, this may be done by manipulating the device 13 by the thumb of the hand holding the torch, leaving the
40 other hand entirely free. If the gas is entirely cut off by the supplemental valve 24, the pilot light will remain burning for the ignition of the mixed gas and air the moment the said valve is again opened. By
45 hanging up the torch by means of its hook 20, the supplemental gas-valve 24 is closed and held closed by the weight of the torch acting through the sliding valve-manipulating device 13, without, however, shutting
50 off the pilot-light gas-supply.

In the modified form shown by Fig. 4 of the drawings, the supplemental gas-valve 33 is mounted upon the extreme inner end of the arm 34 of a sliding valve-manipulating
55 device in the form of a slide 35 extending over and parallel with the gas-pipe 36, the said arm 34 having bearing in a gland 37 mounted in the cast head 38. A spring 39 encircling the arm 34 exerts a constant effort
60 to hold the valve 33 away from its seat 40 which is interposed between two passages 41 and 42 in the head 38, the passage 42 being intersected by the air pipe 43 and being in line with the mixing-tube 44. By

moving the sliding device 35 in one direction or the other by the thumb of the hand holding the torch, the supplemental gas-valve 33 may be entirely or partially closed as called for by the desired content of gas in the mixture. The bend 45 in the wire 70 forming the device 35 constitutes a suspension-loop for the torch, the weight of which will overcome the spring 39 and hold the valve 33 upon its seat 40 so long as the torch
75 is suspended.

In the modified construction shown by Fig. 5, a supplemental gas-valve 46 co-acting with a seat 47 in the head 48, is formed with a perforated hollow valve-stem 49 and normally held away from its seat by a helical spring 50 located in a chamber 51 in the said head. The said valve 46 is operated by a plunger 52 passing through a gland 53 mounted in a threaded bushing 54 in the head 48. The projecting outer end of the 80 plunger 52 is engaged by the arm 55 of a yoke-shaped lever 56 straddling the gas-pipe 57 and hung upon a pin 58 in the head 48. The lever 56 which is furnished with a suspension-hook 59, is operated by a sliding 85 wire 60 extending inward on the outside of the pipe 57 and is provided at its inner end with a loop (not shown) corresponding to the loop 14 or with some other means adapting it to be operated by the thumb of the 90 hand holding the torch. In this construction, the plunger 52, the lever 56, and the slide 60 together form the valve-manipulating device. The gas on leaving the pipe 57 enters a passage 61 in the head 48, passing 95 thence through the perforated valve-stem 49 into the chamber 62 in the head, and thence into the mixing-tube 63 which receives an air-nozzle 64 connected with an air-pipe 65 which is entered into the head 100 48 and extends parallel with the gas-pipe 57. This modified device is operated in substantially the same way as the device of Figs. 1 to 3 inclusive, the difference lying in the mode of operating the supplemental gas-
105 valve 46 which tends to move into its open position.

In the modified construction shown by Fig. 6 of the drawings, a supplemental gas-valve is dispensed with, but the gas-content 115 supplied to the flame is still kept under the control of the user in the same manner as in the devices heretofore described; that is to say, by means of a valve-manipulating device arranged so as to be operated by the 120 thumb of the hand holding the torch concurrently with the use thereof.

In the modified construction shown by Fig. 6, the valve-manipulating device 65^a is secured to a collar 66 located at the inner 125 end of a tube 67 arranged to slide back and forth on the air-pipe 68 which in this form is located on the outside of the torch. The

said tube 67 is furnished at its outer end with a lug 69 forming a support for the forward portion of the slide 65^a which is formed at its rear end with a loop or thumb-piece 70 for engagement by the thumb of the hand holding the torch. The said collar 66 is formed with a slot 71 receiving the inwardly bent arm 72 of the gas-cock or valve 73, whereby the same is opened and closed by the manual longitudinal movement of the valve-manipulating device 65^a. The air-pipe 68 is provided with an air-cock or valve 74 having a handle 75 of ordinary construction. The forward end of the cock 74 is threaded for the application of an adjusting nut 76 which is engaged by the rear face of the collar 66 for which it constitutes an adjustable stop. By adjusting the nut 76 the content of gas supplied by the gas-cock or valve 74 may be easily regulated. The nut 76 having been adjusted as required, it is apparent that the cock 74 will always be opened to the same point when the slide 65 is fully retracted. At its forward end the device 65^a is furnished with a suspension loop 78 by means of which the torch is hung up. The gas-cock or gas-valve 73 is located in a gas-pipe 79 arranged parallel with the air-pipe 68 but on the inside of the torch with respect to the same. The pipes 68 and 79 are entered into a delivery-head 80 furnished with a mixing-tube 81 containing an air-nozzle 82. A small pilot-light pipe 83 leading from the gas-pipe 79 to the end of the tube 81 supplies the gas required for maintaining the pilot-light. Although the construction of Fig. 6 has no supplemental gas-valve, it is characterized by having the gas shut off and turned on by means of a sliding valve-manipulating device operable by the user substantially in the same manner as in the other constructions.

My improved blow torch, as will be seen by the different forms herein shown and described, is characterized by its provision with a valve-manipulating device applied to its outer side over the outer of its two tubes in position to be manually operable for regulating or entirely shutting off the gas supplied to the mixture by the hand employed by the user of the torch for holding it and operating it, the operation of the slide being concurrently with the operation of the torch and without recourse to the use of the user's other hand which is thus left free.

I claim:

1. In a blow torch, the combination with parallel gas and air-pipes, of gas and air-valves for the said pipes, a supplemental gas-valve, and a valve-manipulating device applied to the exterior of one of the said pipes, co-acting with the said supplemental gas-valve and positioned to be operable by

the hand employed by the user to hold and operate the blow torch concurrently with such use of it, the said device being furnished with a suspension-hook for the suspension of the torch in a vertical position and for the closing of the said supplemental air-valve by the weight of the torch.

2. In a blow torch, the combination with parallel gas and air-pipes, of gas and air-valves therefor, a supplemental gas-valve, and a valve-manipulating device applied to the exterior of one of the said pipes so as to slide with respect thereto, co-acting with the said supplemental gas-valve, positioned to be operable by the hand employed by the user to hold and operate the torch, and furnished at its outer end with a suspension-hook for the suspension of the torch in a vertical position and for the closing of the said supplemental air-valve by the weight of the torch.

3. In a blow torch, the combination with gas and air pipes arranged parallel with each other, of valves for controlling the passage of gas and air through the respective pipes, and a sliding, manually operable valve-manipulating device applied to the outer of the two pipes for controlling the gas content of the mixture, the said device being positioned to be operable by the hand employed by the user for operating the torch and provided with a suspension-hook against which the weight of the torch acts to shut off the gas.

4. In a blow torch, the combination with parallel gas and air-pipes, of a head applied to the delivery ends thereof, gas and air-valves for the respective pipes, a supplemental gas-valve located in the said head, and a manually operable valve-manipulating device applied to the exterior of one of the said pipes in position to be operated by the hand employed by the user for holding and operating the torch and to co-act with the said supplemental gas-valve located in the said head and furnished with a suspension-hook for the suspension of the torch in a vertical position, and for the shutting off of the gas by the weight of the torch, at the supplemental gas-valve.

5. In a blow torch, the combination with the gas and air-pipes thereof, of gas and air-valves therefor, and a suspension device co-acting with a gas valve of the torch to close the said valve and cut off the gas by the weight of the torch when the same is hung in a vertical position by the said device, the torch descending with respect to the suspension device by its weight after the suspension device has been engaged with a fixed point for the purpose of hanging up the torch.

6. In a blow torch, the combination with the gas and air-pipes thereof, of a gas-valve,

and a valve-manipulating device applied to the exterior of one of the said pipes so as to slide thereupon, co-acting with the said gas-valve to operate the same, provided with a suspension device and operated by the weight of the torch to cut off the gas when the torch is hung up by the said device.

In testimony whereof, I have signed this specification in the presence of two subscribing witnesses.

ROSS M. G. PHILLIPS.
